US00D919109S

(12) **United States Design Patent** (10) Patent No.: **US D919,109 S**
(45) Date of Patent: **** May 11, 2021**

(54) **UVC LED SEX TOYS STERILIZING BAG**

(71) Applicant: **SHENZHEN UVLED OPTICAL TECHNOLOGY CO., LTD.**,
Guangdong (CN)

(72) Inventor: **Chen Yi Ou Yang**, Ningyuan County (CN)

(73) Assignee: **SHENZHEN UVLED OPTICAL TECHNOLOGY CO., LTD.**, Guangdong (CN)

(**) Term: **15 Years**

(21) Appl. No.: **29/684,305**

(22) Filed: **Mar. 20, 2019**

(30) **Foreign Application Priority Data**

Jan. 11, 2019 (CN) 201930016030.5

(57) **CLAIM**

The ornamental design for an UVC LED sex toys sterilizing bag, as shown and described.

DESCRIPTION

FIG. 1 is a perspective view of an UVC LED sex toys sterilizing bag, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a perspective view thereof in use.

The broken lines in the drawings depict portions of the sterilizing bag that form no part of the claimed design.

1 Claim, 7 Drawing Sheets
